FLUID COMPRESSOR

Frank A. Halleck, Michigan City, Ind., assignor
to Sullivan Machinery Company, a corporation
of Massachusetts

Application May 3, 1934, Serial No. 723,655

17 Claims. (Cl. 230—58)

This invention relates to fluid compressors or pumps, and more particularly, but not exclusively, to improvements in the cooling system of a fluid compressor or pump of the air cooled type.

6 An object of this invention is to provide an improved fluid compressor or pump of the air cooled type. Another object is to provide an improved cooling system for a fluid compressor or pump. Still another object is to provide an 10 improved cooling system for a fluid compressor or pump and having associated therewith improved cooling means for the pump driving motor and the fluid receiver tank. Yet another object is to provide an improved fluid compressor or 15 pump having an improved arrangement of parts whereby the same is rendered extremely compact, the compressor unit being arranged in an improved manner between the driving motor and the receiver tank. Another object is to provide 20 an improved supercharger for the air intake of an air compressor or pump, the said supercharger being associated with the improved cooling system. A still further object is to provide an improved cooling system for a fluid compressor or pump of the radial cylinder type. These and 25 other objects will, however, hereinafter more fully appear.

In the accompanying drawings there is shown for purposes of illustration one form which the 30 invention may assume in practice.

In these drawings—

Fig. 1 is a central longitudinally extending vertical sectional view, with parts in elevation, of the illustrative embodiment of the improved 35 fluid compressor or pump.

Fig. 2 is a cross sectional view taken substantially on line 2—2 of Fig. 1.

Fig. 3 is a side elevational view of the improved 40 compressor unit per se, showing one of the deflector plates.

Fig. 4 is a plan view of one of the compressor cylinders showing a portion of the improved cooling system and the associated supercharger.

Fig. 5 is a detail sectional view taken on line 45 5—5 of Fig. 4.

Fig. 6 is an enlarged vertical sectional view taken through one of the compressor cylinders and showing the improved head structure.

Fig. 7 is a cross sectional view taken substantially on line 7—7 of Fig. 6.

In this illustrative embodiment of the invention there is shown an improved fluid compressor or pump generally designated 1 and generally comprising a fluid compressor or pump unit 2, a driving motor 3 and a receiver tank 4, the ele-

ments 2, 3 and 4 being arranged in an improved manner on a common base 5.

The motor 3 is herein preferably of the air cooled electric type having its rotor 6 horizontally and longitudinally disposed. The casing 7 of this motor is secured to an annular supporting frame 8, herein preferably formed integral with the base 5 and upstanding therefrom in the manner shown. Secured to this annular frame 8, as at 9, is a cylindrical sheet metal housing 10, 10 herein having a longitudinal bottom slot 11 for receiving the pedestal support 12 for the receiver tank 4, and this housing completely encases the compressor unit 2 and a major portion of the receiver tank.

It will herein be noted that the longitudinal axes of the motor, the compressor unit and receiver tank are arranged in substantially longitudinal alignment, with the compressor unit arranged in transverse planes between the adjacent ends of the motor and receiver tank, and the rotor 6 of the motor is pressed on the crank shaft 13 of the compressor unit 2 so that the motor rotor and compressor crank shaft are united as one and rotate as a unit.

25 The compressor or pump unit is herein of the radial type and comprises a casing 14 secured, as by bolts, to an end plate 15, the latter in turn having radial arms 16 secured, as by bolts, to the annular supporting frame 8, the arms 16 and 30 end plate forming the support for the complete compressor unit. Also secured to the casing 14 at the side thereof opposite from the end plate 15 is an end plate 17, and the plates 15 and 17 support ball bearings 18 and 19, respectively, in 35 which the compressor crank shaft 13 is journaled. The plate 17 may be readily removed from the casing 14 to obtain access to the interior of the casing. The compressor unit is herein of the three-cylinder type and comprises cylinders 20 40 secured to the casing 14 at angles spaced 120° apart, each cylinder having a flange 21 secured by bolts 22 to the casing 14. Although there are three cylinders disclosed herein, it will be evident that more or less may be employed, if desired. As shown in Figs. 6 and 7, each of the cylinders 20 is provided with a flange 23 to which there is secured by bolts 24 a cylinder head 25 of improved design, there being interposed between the cylinder head and flange 23 cooperating plates 26 and 27 which respectively support inlet and discharge valve mechanisms 28 and 29, this valve structure being similar to that disclosed in my copending application, Serial No. 583,373, filed 50 55

Dec. 26, 1931, now matured into Patent No. 1,996,762, in general disposition of the parts.

Reciprocably mounted in the bores 30 of each of the cylinders is a piston 31, and as shown in Fig. 1, the piston of the upper cylinder is connected by a connecting rod 32 to the crank 33 of the crank shaft 13, and one of the lower cylinders has a connecting rod 34 pivotally connected at 35 to the connecting rod 32, the other cylinder 10 being similarly connected in this latter manner.

As previously mentioned, the motor 3 and the compressor unit are air cooled, and the improved cooling means comprises a fan 40 having its hub keyed to the compressor crank shaft 13 and arranged between the adjacent sides of the motor and compressor unit in the manner shown in Fig. 1. This fan draws cool air through openings 41 formed in the motor casing and through the open inner side of the motor casing and the aligned opening 42 in the annular supporting frame 8, and also draws cool air through openings 43 in the outer wall of the annular supporting frame 8, and blows the cool air so drawn toward the compressor unit and receiver tank, the fan operating 20 in the cylindrical casing 10 and blowing the cool air longitudinally therethrough. Arranged between the radially located cylinders of the compressor unit are sheet metal deflector plates 44, each having its opposite sides converging inwardly toward the cylinders so that the air blown toward the compressor unit by the fan is directed by these deflector plates toward the cylinders, there being provided openings 45 between the inner edges of the deflector plates and the cylinder walls so that the air is blown past the cylinders toward the receiver tank. To aid in cooling of the cylinders and cylinder heads there are provided radial heat-radiating fins 46 formed circumferentially about the outer wall of the cylinders and transversely arranged heat-radiating fins 47 formed in parallelism on the tops of the cylinder heads, the cooling air being blown across the tops of the heads in a direction lengthwise of the fins 47.

Again referring to the improved head structure for the cylinders, and more particularly to the improved supercharger associated with the cooling means, it will be noted that formed centrally within each of the heads 25 is an opening 48, 45 while arranged centrally within this opening at the inner side of the head is a fluid-deflecting portion 49 by which the fluid flowing through the intake passage 46 is directed toward the inlet openings of the inlet valve mechanism. The discharge valve mechanism discharges the compressed fluid into an annular chamber 50 encircling the intake opening 48 and connected by a discharge pipe 51 to the receiver tank 4. To aid in the cooling of the receiver tank, the latter 50 is provided with radially located heat-dissipating fins 52 formed longitudinally along the exterior of the tank, these fins, as the air is blown longitudinally toward the tank and through the cylindrical casing 10, tending to lower the temperature of the air within the receiver tank.

Now referring to the improved supercharger for the compressor intake, it will be noted that a curved pipe or pipe elbow 53 is secured herein to each cylinder head, by bolts 54 engaging lateral lugs 55 formed integral with the pipe elbow, and these lugs are heat-insulated from the compressor cylinder by suitable insulating material 56 interposed between the lugs and the cylinder head. One end of this curved pipe is directed 70 axially inwardly within the opening 48 in the

cylinder head to a position wherein the inner end thereof lies adjacent the deflecting portion 49 of the cylinder head, while the opposite end of this pipe is directed rearwardly so that the mouth thereof is bent towards the inner side of the fan 5 40, so that a certain amount of the air blown by the fan towards the compressor unit is directed into the mouth of these curved pipes, directly into the intake opening of the cylinder heads so that the air conducted past the inlet 10 valve mechanism 28 into the compressor cylinders is at a pressure slightly higher than atmospheric, any surplus air flowing outwardly from the intake opening in the space between the pipe and the inner walls of the opening, thereby to aid 15 in the cooling of the heads. The cylindrical casing 10 is cut away at 57 to receive the outer curved portions of the supercharger pipes, as shown in Figs. 1 and 2.

As a result of this invention, it will be noted 20 that an improved fluid compressor or pump is provided of the air cooled type having improved cooling means whereby the elements of the compressor are maintained at relatively low operating temperatures. It will further be noted that 25 by arranging the elements of the compressor in the manner disclosed and housing the compressor unit and receiver tank, the compressor is rendered extremely compact while the vital parts thereof are effectively shielded. It will further 30 be evident that by the provision of this improved cooling means, it is possible to direct a certain quantity of the cooling fluid at a pressure above atmospheric into the compressor cylinder intakes, thereby to form an intake supercharger 35 resulting in a compressor of greater overall efficiency. These and other advantages of the improved compressor will be clearly apparent to those skilled in the art.

While there is in this application specifically 40 described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a fluid compressor, a base, a motor on 50 said base, a compressor unit on said base driven by said motor and having cylinders disposed above and below the motor axis, an elongated substantially cylindrical receiver tank on the base connected with the compressor unit discharge, said motor, compressor unit, and tank axes arranged in substantial alinement, and means including a fan coaxial with the compressor unit for causing a concentrated flow of cooling fluid past each cylinder and yet providing for 60 cooling the top, bottom, and sides of said receiver tank.

2. In a fluid compressor, a cylinder having an intake opening, air cooling means for said cylinder, and means associated with said cooling 65 means for conducting air under pressure to said compressor cylinder intake and comprising a conduit for receiving a quantity of the cooling fluid and having a portion projecting within said intake opening for conducting the cooling fluid to 70 the compressor cylinder intake.

3. In a fluid compressor, a cylindrical housing, a motor carried at one end of said housing, a compressor unit arranged in said housing, air cooling means for said compressor unit compris- 75

- ing a blower fan driven by the motor and arranged in said housing between said motor and compressor unit for blowing air longitudinally through said housing, and a receiver tank supported within said housing and having cooling fins along which the air blown through said housing flows for dissipating the heat in said tank.
4. In a fluid compressor, a cylindrical housing, a motor carried at one end of said housing, a compressor unit arranged in said housing, air cooling means for said compressor unit comprising a blower fan driven by the motor and arranged in said housing between said motor and compressor unit for blowing air longitudinally through said housing, and a receiver tank supported within said housing and having cooling fins along which the air blown through said housing flows for dissipating the heat in said tank, said tank arranged within said housing with its longitudinal axis alined with the compressor unit and motor axes and coincident with a portion of the housing axis.
5. In a fluid compressor, a base providing an upstanding annular support, a cylindrical housing secured to said annular support, a motor having its casing secured to said support and arranged with its axis alined with the central line of said cylindrical housing, a compressor unit arranged within said housing and driven by said motor and having cylinders extending from points adjacent the inner wall of said housing radially towards the axis thereof, cooling means for said compressor unit comprising a blower fan driven by said motor and arranged between said motor and compressor unit for blowing cool air longitudinally past said compressor unit through said cylindrical housing and means for limiting flow of air through the sectors between the compressor cylinders.
6. In a fluid compressor, a base providing an upstanding annular support, a cylindrical housing secured to said annular support, a motor having its casing secured to said support and arranged with its axis alined with the central line of said cylindrical housing, a compressor unit arranged within said housing and driven by said motor, cooling means for said compressor unit comprising a blower fan driven by said motor and arranged between said motor and compressor unit for blowing cool air longitudinally past said compressor unit through said cylindrical housing, and a receiver tank projecting within said housing and arranged with its axis alined with the axes of said motor and compressor unit and over which the air blown through said housing flows.
7. In a fluid compressor, a base having an upstanding annular support thereon, a cylindrical housing secured to said annular support, a motor having its casing secured to said support and arranged with its axis alined with the central line of said cylindrical housing, a compressor unit arranged within said housing and driven by said motor, cooling means for said compressor unit comprising a blower fan driven by said motor and arranged between said motor and compressor unit for blowing cool air longitudinally past said compressor unit through said cylindrical housing, and a receiver tank projecting within said housing and arranged with its axis alined with the axes of said motor and compressor unit and over which the air blown through said housing flows, said tank having longitudinally extending peripheral cooling fins for dissipating the heat of said tank as the air is blown through said housing by said fan.
8. In a fluid compressor, a cylinder having a head, said head having an intake opening, and a curved pipe secured to said head by bolts and heat-insulated from said head, said pipe having a portion projecting centrally within said intake opening.
9. In a fluid compressor, a base, a motor on said base, a compressor unit on said base driven by said motor, an elongated receiver tank arranged lengthwise on said base and supported above the bottom of the latter to permit cooling fluid flow along the lower side thereof, said motor, compressor unit, and receiver tank arranged in end to end relation on said base, a fan driven by power from said motor, and means for directing and maintaining air flow in contact with said compressor unit and the peripheral walls of said tank.
10. In a fluid compressor, a base, a motor on said base, a compressor unit on said base driven by said motor, a receiver tank on said base connected with the compressor unit discharge, said motor, compressor unit and receiver tank disposed coaxially, a fan driven by power from said motor, and means for concentrating the flow of the air displaced by said fan adjacent the compression spaces of said compressor unit as it passes the latter and causing the flowing air to pass in an annular stream about the periphery of said receiver tank.
11. In a fluid compressor, a cylinder having an intake opening surrounded by a wall forming a boundary for said opening, air cooling means for said cylinder, and means associated with said cooling means and including conduit means leading to said intake opening and cooperating with said wall to provide two distinct passages leading to the compressor intake opening, said conduit means constituting passage means for conducting air under pressure to said compressor intake opening, and the space between said conduit means and said wall providing a second distinct intake passage in free communication with the atmosphere.
12. In a fluid compressor, a cylinder having an intake opening communicating with the atmosphere, air cooling means for said cylinder, and means associated with said cooling means for conducting air under pressure to said compressor cylinder intake and comprising a conduit for receiving a quantity of the cooling fluid and having a portion projecting within said intake opening for conducting the cooling fluid to the compressor cylinder intake.
13. In a fluid compressor, a cylinder having an intake opening, air cooling means for said cylinder including a device for creating a flow of air and deflecting devices for diverting air passing laterally of said cylinder towards the latter, and means disposed adjacent the zone of maximum air flow for taking, prior to its reaching said cylinder, and conducting air under pressure to said compressor cylinder intake opening.
14. In combination, a casing, a compressor therein, having cylinders extending radially of said casing, deflectors intermediate said cylinders for deflecting air laterally onto said cylinders, and means for creating a flow of air through said casing and over each of said cylinders.
15. In combination, a compressor having a plurality of cylinders, means for creating a flow of cooling fluid past said cylinders in parallel, means for confining the path of flow to the zone

of said cylinders, and deflecting means between said cylinders for directing fluid which would otherwise pass between the same towards and onto said cylinders.

- 5 16. In a fluid compressor, a cylinder having an intake opening, an annular inlet valve communicating substantially completely around its periphery with said intake opening, a device in said intake opening for deflecting air substantially uniformly to the different circumferential portions of said valve, and means for delivering air to said intake opening at a pressure above atmospheric, discharging axially upon said de-
- 10

flecting device, whereby said valve takes air at an increased rate substantially uniformly about its periphery.

17. In a fluid compressor, a cylinder having an annular inlet valve and having an annular passage leading to said inlet valve, and means including coaxial-passage-forming devices respectively providing passages for conducting air at atmospheric pressure and for conducting air at a higher pressure to said valve, arranged coaxial- 10 ly with the latter.
